(57) **CLAIM**

The ornamental design for a toy mini flying saucer, as shown and described.

DESCRIPTION

FIG. 1 is a perspective view of a toy mini flying saucer embodying my design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left elevational view thereof; and,

FIG. 7 is a right elevational view thereof.

The broken lines are included for the purpose of illustrating portions of the toy that form no part of the claimed design.

The appearance within the unshaded areas forms no part of the claimed design.
